UNITED STATES PATENT OFFICE.

ALFRED MARSHALL, OF LEICESTER, ENGLAND.

PRESS.

No. 821,517.

Specification of Letters Patent.

Patented May 22, 1906.

Application filed March 13, 1905. Serial No. 249,927.

To all whom it may concern:

Be it known that I, ALFRED MARSHALL, printer and gold-blocker, a subject of the King of Great Britain, residing at 36 Friar 5 Lane, Leicester, in the county of Leicester, England, have invented certain new and useful Improvements in or Relating to Presses, of which the following is a specification.

This invention relates to presses such as 10 are used in gold blocking or embossing—*i. e.*, printing in gold, silver, and the like letters and designs such as are used on the top bands and socks of boots and shoes and upon the 15 bindings of books, hat sweat-bands, and labels for crowns of hats and for other purposes hereinafter referred to as the “work.”

In machines as at present employed the chase, which carries the type or design, is furnished with a handle by which the operator 20 inserts it by hand into the fire-box and removes it therefrom at each blocking operation.

In a press constructed according to this invention a carrier for the chase is provided 25 which obviates the frequent handling in the manner hereinbefore mentioned of the chase and the loss of time incident thereto, and this carrier may be of a somewhat different construction, according to the type of press to 30 which it is applied.

According to one form of press a track or carrier for the chase is provided, so that the chase may be slid along into a position into alinement with the gold or other leaf (hereinafter referred to as “gold-leaf”) to be transferred to the work, or instead of being slid the chase may be connected to a carrier, so that it can be swung into position to receive the gold-leaf. The pile or sheets of gold-leaf 40 to be applied to the face of the chase may be supported on a table having a universal adjustment in relation to the chase.

The invention will be more clearly understood from the following description, in which 45 reference is made to the accompanying drawings.

Figure 1 is a front view of a complete press constructed according to one form of this invention, and Fig. 2 is an end view of the 50 same. Fig. 3 shows a plan of the feed-table for carrying the gold-leaf and its supports. Fig. 4 is a section on the line *a b* of Fig. 2 through the fire-box, showing the manner in which it is supported; and Fig. 5 is an under 55 side view of the head of the press from which the fire-box is supported. Fig. 6 shows the

arrangement of the oil-pad. Figs. 7 and 8 are a plan and vertical section, respectively, of the platen and frisket-fingers. Figs. 9 and 10 are similar views to Figs. 1 and 2 of a modified arrangement; and Figs. 11 and 12 show in end view and plan, respectively, a further method of supporting and operating the chase.

Like parts are designated by similar reference-numerals in all the figures, and Figs. 4 to 8 are drawn to a larger scale than the other figures.

In the drawings, 5 is the chase, which carries the die 2, the face of which is supplied 70 with gold or other leaf without the chase being removed from the press for that purpose, and for brevity's sake both the chase and the die are hereinafter referred to as the “chase.”

3 is a feed-table carried by the machine 75 and adapted to support the pile of sheets of gold or other leaf between which table 3 and the fire-box the chase is adapted to be reciprocated, and 4 is the platen, which is adapted to be moved and pressed up against the chase, 80 so that the work carried thereon may receive the impressions and leaf from the heated chase.

The type or die 2 is located in and carried 85 by the chase 5, in which it is securely held in its correct position relatively to the platen 4 by means of a screw 5^a, Fig. 1, in the well-known manner. The chase 5 is supported from the fire-box 6 by having its upper surface grooved or recessed to adapt it to engage 90 the said fire-box, and also a carrier, track, or race projecting laterally therefrom along which it is reciprocated, as hereinafter described. The chase 5 is held in place, so as to have a sliding fit on the track by means of 95 overhanging metal strips 5^b, Fig. 2, attached one at each side thereof by screws 5^c. The fire-box 6, by which the chase is heated, is supported from the head 7^a of the main frame 7 of the press by spiral springs, hereinafter referred to. For this purpose the upper surface of the said fire-box is provided with 100 upstanding studs 9, and in fitting the fire-box in position these studs are passed through corresponding holes in the head 7^a and provided 105 each with a spiral spring 8 and a nut 10. The said fire-box is formed with chambers to receive the perforated gas-pipes 11 or other suitable means for heating the same. The adjustment of the chase relatively to the 110 platen is effected by means of the said springs and nuts aforesaid and also by means of

wedges 12, Fig. 4. The said wedges 12 are located in taper grooves 13, formed in the under surface of the said head 7^a and bear against the upper surface of the fire-box 6. 5 The wedges are forced in by means of screws 14 or in any other well-known manner and their action is opposite to that of the springs 8. The said carrier track or race consists of a longitudinal metal plate 15, which, in the 10 form shown most clearly in Figs. 1 and 4, is cast integrally with the fire-box 6 and projects laterally horizontally therefrom. The longitudinal edges are trued so as to form an even surface for the chase 5 to slide on, as 15 above described. The chase may be moved along this race or track by the hand of the operator to the point where it receives the gold or other leaf from the table 3 and back to the fire-box 6, and vice versa, or mechanism 20 may be employed for that purpose. According to one arrangement the reciprocating movement of the chase 5 is obtained through intermediate mechanism from a foot pedal or lever (not shown) and a spring 25. For this 25 purpose a bell-crank lever is employed, one arm 16 of which is connected by a rod 17, reaching down to the said foot-pedal. The other arm 18 of the bell-crank lever has formed on its free end a cam edge 18^a, which 30 bears edgewise against the adjacent curved arm 19 of a second lever, the other arm 20 of which projects upward toward the chase 5 and is connected by a link 21 to a pin 22, projecting from the said chase. The bell-crank 35 lever 16 18 and the second lever 19 20 are each mounted on pivots 16^a 19^a, respectively, supported by a bracket 23, bolted to the main frame of the press. The arm 18 is prevented 40 moving laterally relatively to the edge of the curved arm 19 by means of two plates 24, bolted or otherwise secured one on each face of the said curved arm 19. The edges of the plates 24 project beyond the edge of the arm 19, so as to form a guide for the cam edge of 45 the said arm 18 of the bell-crank lever. It will be seen that on depressing the foot-pedal so as to lower the rod 17, and hence the arm 16 of the bell-crank lever, the end of the arm 18 will, as it moves to the right, slide along 50 the curved edge of the arm 19 and in doing so will move the said arm 19 to the right also and its opposite arm 20, connected to the chase 5, to the left, thus effecting the outward movement of the chase from the fire-box to the feed-table. 55 The return motion of the lever 19 20, and therefore of the chase, to the fire-box is effected by the spring 25, attached at one end to an intermediate point in the arm 20 and at the other end to the framework 60 of the press. The chase during its travel along the track or carrier 15 and before it comes opposite the table 3 makes a rubbing contact with an oiling-pad, which greases the surface of the same, and thereby enables it to 65 pick up and retain the gold-leaf with more

certainty than if such surface had not been greased.

The chase as it comes opposite the oiling-pad raises the latter automatically, so as to make contact therewith, after which the pad drops down of its own weight out of the path of the chase as the latter returns from the gold-leaf table 3. The upward movement of the oiling-pad is effected upon the outward motion of the chase along the track 15, as will 75 be hereinafter pointed out.

The oiling-pad 26 is carried by an arm 27, Figs. 2 and 6, hinged at 27^a to the lower extremity of a bracket 28, secured by screws or the like to the track 15. Between the pad 26 and the hinge 27^a the arm 27 is provided with an upstanding lifting-plate 29, the upper end of which is reduced to pass through a hole in the upper portion of the bracket 28 and carries a nut or equivalent 30, forming a stop. The said lifting-plate is slotted to carry a lug 31, and the pad is raised by means of a hinged cam-piece 32, Fig. 1, carried by the forward end of the chase, engaging and lifting the said lug 31 as the chase passes along. The extent 90 of the upward movement of the pad may be adjusted by altering the position of the said lug 31 in its slot by means of the nut 33, as shown in Fig. 6. The movements of the chase to and fro along the track 15 are limited by a stop 34 on the said carrier in the outward direction and by the fire-box in the return direction.

The pile of sheets of gold or other leaf is supported upon the feed-table 3, which comprises an open box or framing 3^a, the floor of which consists of two wedge-shaped blocks 35 37, oppositely disposed. The movement of the lower block 35 in one direction, by the turning of the adjusting-screw 36 or other well-known means, raises the upper block 37, upon which the gold-leaf is carried, so that notwithstanding the reduction in the height of the pile of sheets, due to their being taken one by one by the chase, the top sheet is always maintained capable of making contact with or is raised sufficiently high to meet the chase. The said feed-table is arranged to have a universal adjustment—*i. e.*, it is adjustable in transverse, lateral, and vertical directions to insure the gold-leaf coming into contact with the whole surface of the chase when the operator raises the table or its supporting-rod by hand for that purpose.

The transverse direction of adjustment is effected by mounting the table upon a transverse rod 38, supported at one end by a standard 41, projecting laterally from one end of the press, the said feed-table being provided at its under side with a socket 39, which is squared to engage a similar squared portion of the rod 38. The table when adjusted to its required position on this rod is locked, so far as transverse adjustment is concerned, by a set-screw 40. The lateral adjustment 130

of the table is obtained by mounting the rod 38 on the laterally-projecting standard 41 by a socket connection, so that it may be slid therealong and locked in any desired position by means of a thumb-nut 42, which engages a thread on the reduced outer end of the said standard and bears against the socketed extremity of the rod 38. A spring 43, embracing a reduced portion of the standard 41, normally forces the rod 38 toward the outer end of the standard and permits of the said rod 38 being turned about the standard 41 to raise the table up to the chase. The said standard is carried by a bracket 41^a, bolted to the framework 7 of the press and provided with a vertical slot, so that the bolts 41^b on being loosened permit the said bracket and standard and hence the rod 38 and table 3 to be adjusted in a vertical direction.

The gold-leaf table 3 normally rests on a stop 45, carried by one end of an arm 46, the other end of which screws into and is carried by one end of the frame of the press.

The platen 4, Figs. 2, 7, and 8, upon which the work to be blocked or embossed is placed, is fulcrumed at 47 to the framework, so as to move in an arc of a circle relatively to the chase. This platen may be raised up to the chase by any suitable mechanism; but a convenient arrangement consists of toggle-levers 48 49, operated by a hand-wheel 50. The toggle-lever 49 is secured at one end to the spindle 54 of the hand-wheel, and at the other end it is hinged to the adjacent end of the other toggle-lever 48, whose opposite end is pivoted to the under side of the platen. The hand-wheel 50 is provided on its periphery with a stud 51, adapted to come in contact with a stop 52 when the toggles are in line with one another and full force thereby contained. The stop 52 is bolted to the table or bed upon which the press is supported.

On the face of the platen is a pair of frisket-fingers 55 or equivalent, Figs. 7 and 8, under which the work to be embossed or blocked is held, and these fingers are caused to press upon the work and hold it in position on the platen 4 as the latter rises to the chase, and thus prevent the work shifting as the platen becomes more inclined. One method of effecting this is by attaching to the slotted base-strip 56, to which the said fingers are adjustably secured by thumb-screws 57, a tail or extension 58, which contacts with a projection 59, bolted to the frame 7 of the press, and forces the fingers 55 down onto the work as the platen rises. The said base-strip 56 is pivoted at 60 to an intermediate point in the under part of the platen.

The operation of the press is as follows: A pile of sheets of gold or other leaf having been placed upon the feed-table 3, one operator depresses the foot-pedal, which, through the medium of the rod 17 and levers 16 18 and 19

20, causes the chase to be moved outward away from the fire-box along the track 15, passing in contact with the oiling-pad and finally coming to rest in a position in alignment with the feed-table 3. The same operator now raises the table by hand up to the chase by means of the projecting outer end of the rod 38, so as to feed the gold or other leaf to the surface 2 of the chase. During this operation a second operator places the work to be embossed on the platen 4 beneath the frisket-fingers, and by the time this is accomplished the first operator has released the foot-pedal, whereupon the spring 25 returns the chase to the fire-box. The second operator now rotates the hand-wheel 50, thus raising the platen up against the chase with more or less pressure, with the result that the work carried thereon is embossed or blocked according to the design of the die 2.

In an alternative arrangement (shown in Figs. 9 and 10) the chase when moved outward into alignment with the table 3 is adapted to be swung down onto the said table instead of the latter being raised up to meet it, as above described. For this purpose the track preferably comprises two horizontal bars 65 66, Figs. 9 and 10, supported at one end by a bracket 67, carried at the outer end of a horizontal stay 68, projecting laterally from the framework 7, into which its other end is screwed or otherwise securely fixed thereto. The chase is supported on the track-bars 65 66 by means of split lugs 69, arranged, say, two on one side of the chase and one on the other side. At a point 65^a on the track-bar 65 opposite the table 3 the diameter of the bar is reduced, so that when the chase is moved along the track by the means and in the manner substantially as described the single split lug 69 on that side the chase when it reaches the reduced part 65^a of the bar 65 allows the said chase to swing down onto the table 3, the other bar 66 acting as a pivot or hinge, as shown in broken lines in Fig. 10. When it is desired to move the chase altogether from the track, it must be moved farther to the left, Fig. 9, until the split lugs 69 on the other side of the said chase reach the reduced portions 66^a of the bar 66, on which they ride, when the whole chase may be removed. The universal adjustment of the table is the same in this construction as hereinbefore described.

Figs. 11 and 12 illustrate a further method of supporting and operating the chase. In this arrangement the chase is rigidly connected to or formed integral with an arm or carrier 70, so that it can be swung thereby into position to receive the gold-leaf. To effect this purpose, the said carrier is pivoted at its free end on a pin 71, carried by a bracket 72, bolted to the framework 7 of the press, as shown. The arrangement is such that the

chase when in the position indicated in full lines in Fig. 12 is in its correct position beneath the fire-box and above the platen 4. In order to feed the face 2 of the chase with 5 gold or other leaf, the carrier 70 with the chase is swung round on the pivot 71 along the curvilinear path (shown in dotted lines in Fig. 12) until the chase 5 occupies the position shown in dotted lines in the same figure, 10 where it is in alinement with the feed-table 3. The movement of the carrier in this latter direction is limited by a stop 73, carried by the bracket 72. The feed-table 3 is now raised by hand, so as to feed a sheet of gold or other 15 leaf to the surface of the chase, after which the latter is swung back until it again occupies the position beneath the fire-box 6. (Shown in full lines in Fig. 12.) The movement of the chase in this direction also is limited by a stop 74, carried by the fire-box. 20 The movements of the chase may be facilitated by means of a handle 75, fitted to the carrier, as shown. The construction and adjustment of the table are the same as that described for the press, (illustrated in Figs. 1 25 and 2,) as are also the arrangement and operation of the platen in relation to the chase.

What I claim, then, is—

1. In a press of the character described, 30 the combination of a feed-table for sheets of gold or other leaf, a chase movable to bring it into or out of operative relation to the table, means for operating one of said elements to cause the sheets of gold or other leaf to be 35 brought into contact with the chase, and a fire-box toward and from which the chase is movable all as described for the purposes specified.

2. In a press of the character described, 40 the combination of a feed-table for sheets of gold or other leaf, a chase movable to bring it into and out of operative relation to the table, means for operating one of said elements to cause the sheets of gold or other leaf to be 45 brought into contact with the chase, a fire-box toward and from which the chase is movable, and an oiling device arranged in the path of movement of the chase and adapted to oil the chase, for the purpose specified.

50 3. In a press of the character described, the combination of a feed-table for sheets of gold or other leaf, a chase movable to bring it into and out of operative relation to the table, means for operating one of said elements 55 to cause the sheets of gold or other leaf to be brought into contact with the chase, a fire-box toward and from which the chase is movable, an oiling-pad, and means for bringing the pad into contact with the chase during 60 the movement of the latter away from the fire-box and before receiving the sheet of gold-leaf.

65 4. In a press of the character described, the combination with a fire-box, and a race or track, of a chase mounted and adapted to

slide upon said track toward and away from the fire-box, and means for moving the chase comprising a foot-pedal, a pivoted bell-crank lever having one arm connected with the foot-pedal, a second two-armed lever against 70 one arm of which the other arm of the bell-crank lever is adapted to bear, and a link connected at one end to the other arm of said second lever and the other end of said link being connected with the chase. 75

5. In a press of the character described, the combination with a fire-box and a chase movable toward and away from the fire-box, of a feed-table for the sheets of gold or other leaf, and adapted to be moved relatively to 80 the chase to bring the uppermost sheet into contact with the chase.

6. In a blocking or embossing press the combination with a fire-box, the chase and a carrier upon which the chase can be moved 85 to and fro relatively to the fire-box, of an oiling device arranged in such a manner that the chase passes in contact therewith as it approaches the feed-table and passes clear of it on returning to the fire-box for the purpose 90 described.

7. In a blocking or embossing press the combination with a fire-box, the chase and a carrier therefor, of an oiling device and means on the said chase to move the oiling device 95 into contact with the chase after the latter leaves the fire-box for the purpose described.

8. In a blocking or embossing press the combination with the fire-box, the chase and a carrier for the chase, of means for automatically greasing the working face of the said chase as it leaves the fire-box for the purpose 100 described.

9. In a blocking or embossing machine the combination with the chase and a carrier 105 therefor of a feed-table carrying the pile of sheets of gold or other leaf having a universal adjustment in relation to the said chase and said chase being arranged and adapted for movement into operative position relatively to the table so as to receive the sheets of gold or other leaf, for the purpose 110 described.

10. In a press of the character described, the combination with a fire-box and a chase 115 movable toward and away from the fire-box, of a feed-table for the sheets of gold or other leaf arranged and adapted to be swung in an arc of a circle to bring the uppermost sheet of gold-leaf into contact with the chase. 120

11. In a press of the character described, the combination with a fire-box and a chase movable toward and away from the fire-box, of a feed-table for the sheets of gold or other leaf arranged to be swung in an arc of a circle 125 to cause the uppermost sheet of gold or other leaf to be brought into contact with the chase, and means for universally adjusting the table relatively to the chase, for the purpose specified. 130

12. In a press of the character described, the combination with a fire-box and a feed-table for the sheets of gold or other leaf, of the chase, a carrier upon which the chase is movable to and fro between the fire-box and feed-table respectively, and a platen having frisket-fingers arranged to exert pressure on the work as the platen approaches the chase and to release the work on the return of the platen.

13. In a press of the character described, the combination with the fire-box, a chase movable toward and from the fire-box and a carrier for the chase, of a platen, a series of toggle-levers and a hand-wheel for raising and lowering the said platen.

14. In a press of the character described, the combination with a fire-box, of a chase movable toward and from the fire-box, a feed-table for the sheets of gold-leaf consisting of 20 two oppositely-disposed wedge-shaped blocks and means for moving one block so as to raise the other block to compensate for the reduction in the pile of sheets and to insure that the top sheet shall always meet the face of 25 the chase.

In witness whereof I have hereunto set my hand in presence of two witnesses.

ALFRED MARSHALL.
